United States Patent Office.

ADAM COLLIGNON, OF CLOSTER, NEW JERSEY.

Letters Patent No. 84,344, dated November 24, 1868.

IMPROVED FOLDING CHAIR.

The Schedule referred to in these Letters Patent and making part of the same.

To all whom it may concern:

Be it known that I, ADAM COLLIGNON, of Closter, in the county of Bergen, and State of New Jersey, have invented a new and improved Folding Chair; and I do hereby declare that the following is a full, clear, and exact description thereof, which will enable those skilled in the art to make and use the same, reference being had to the accompanying drawings, forming part of this specification.

This invention relates to chairs that are made to fold up, whereby they are rendered much more convenient for storage and transportation than chairs of ordinary construction.

The invention consists in hinging or joining the parts of the chair together, so that the same may be folded into a very small space, as will be hereinafter described.

Figure 1 represents a side elevation of the chair.

Figure 2 is a front view of the same.

Figure 3 is a side view, representing the chair as partly folded.

Similar letters of reference indicate corresponding parts.

A represents the back stands of the chair. The back is formed of these two stands, with slats and rounds connecting them in the usual manner. These stands form the front legs.

B represents the back legs.

A and B cross each other on the sides of the chair, as seen at C, where they are joined together by pin or pivot-joints.

The upper ends of the parts B support the front part of the seat D, where the seat is connected to them by pin or pivot-joints, as seen at e.

f is a round, connecting the stands A of the back,

upon which round the back part of the seat rests, as seen in fig. 1.

G represents the arms of the chair.

These arms are pivoted to the back stands A, as seen at h.

The upper ends of the legs B are connected with the arms by the straps i, which straps form swinging joints, being connected at each of the ends by pivots, as seen at j.

In folding up the chair, the seat is raised from the round, f, and turned over on its pivots e, so that when the chair is folded it occupies a position parallel with the back, as indicated in fig. 3, with the bottom side of the seat outermost.

The joint-straps i allow the arms and the front, B, to separate, as seen in fig. 3, so that the whole is made to fold together in a very compact manner, which is a great convenience in either transporting or storing the chair.

I claim as new, and desire to secure by Letters Patent—

1. In combination with a folding chair, the straps i, connecting the arms with two of the legs of the chair in such a manner as to allow the chair to be folded, substantially as described.

2. The arms G, hinged to the back, and connected with the legs B, substantially as specified.

The above specification of my invention signed by me, this 19th day of September, 1868.

ADAM COLLIGNON.
